UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed March 31, 1923. Serial No. 629,019.

To all whom it may concern:

Be it known that I, SAMUEL B. WILLIAMS, a citizen of the United States of America, residing at Brooklyn, in the county of

5 Kings and State of New York, have invented certain new and useful Improvements in Telephone Systems, of which the following is a full, clear, concise, and exact description.

10 This invention relates to telephone systems and more particularly to systems employing automatic switching apparatus for the establishment of connections.

The object of the invention is to secure 15 a more efficient and flexible switching arrangement by an improved method of distributing the selector switches which receive incoming calls and by assigning certain common controlling equipment to said 20 switches in accordance with the distribution thereof.

A feature of the invention is the arrangement of a plurality of selective switches to 25 which incoming calls are distributed, in a number of groups, together with a registering and controlling equipment for each group for selectively operating any switch in the corresponding group.

A further feature relates to the provision 30 of a number of registering devices and a common controlling device for each group of switches, said controlling device being 35 associable with any registering device and with any switch of the group to which it belongs for operating such switch.

Another feature relates to an arrangement, in a system designed to receive a number of classes of calls, whereby calls of a 40 number of different classes may be routed to each of the several groups of switches, each group having its individual controlling equipment for serving all switches therein.

Other features and advantages contemplated by the invention will be taken up in 45 detail hereinafter and pointed out in the appended claims.

Considering the drawing, Figs. 1 to 12, inclusive, taken in the order illustrated in Fig. 13 disclose the details of a telephone system incorporating the features of the present invention. Fig. 1 illustrates a line switch of the coordinate type in which the subscribers' lines terminate and also two of a number of trunks outgoing to a district selector switch.

Fig. 2 shows certain control elements associated with an outgoing trunk.

Fig. 3 discloses a district selector switch of the coordinate type.

Fig. 4 illustrates a group selector switch 60 of the coordinate type in which terminate trunks incoming from the district selectors.

Fig. 5 shows a coordinate connector switch for completing connections to called lines.

Fig. 6 represents a sender selector switch 65 also of the coordinate type.

Figs. 7 and 8 illustrate one of a number of common register senders.

Fig. 9 shows, at the left of the sheet, a 70 sender connector device for connecting any of the senders with the district marker or selection controlling device.

The remainder of Fig. 9 together with Fig. 10 disclose the common marker for controlling the district switches.

Fig. 11 shows a sender connector device 75 for connecting the line marker with any of the several register senders. This figure also shows testing relays for testing the condition of trunks interconnecting the group selector and connector switches together with certain control elements of the line marker.

Fig. 12 discloses the remainder of the 80 line marker.

Figs. 14 and 15 comprise a schematic showing of a telephone system employing switches and controlling equipment arranged in accordance with the principles of this invention.

Referring first to Figs. 14 and 15, the subscribers' lines entering the exchange appear as calling lines in a number of coordinate line switches. If the lines are of different classes they may be conveniently 95 grouped to appear in the line switches according to the class. For example flat rate lines may appear in a group of line switches 1400 of which two switches 1403 and 1404 are shown. Message rate lines appear in the group 1401 of which one line switch 1405 is illustrated. Also coin box lines may appear in the third group 1402 represented by the single line switch 1406.

The first group selector or district switches 100 are arranged in a number of selector groups particularly suitable to the method in which the controlling apparatus exercises its control over these switches. Three of these groups 1407, 1408 and 1409 are illustrated. 110

Group 1407 comprises a plurality of district selector switches 1411, 1412, 1413 and 1414. The second group 1408 comprises a series of district selectors 1415, 1416, 1417 and 1418 while the third group 1409 includes a number of district switches 1419, 1420, 1421 and 1422. The trunks 1410 and 1430 outgoing from the line switches of the group 1400 are shown distributed in any arbitrary manner to the district switches of the several selector groups. Some of these trunks lead to switch 1411, others to the switch 1415, others to the switch 1419, and still others lead to other switches in each of the different selector groups. This distribution of the trunks is purely arbitrary and may be varied to suit the traffic requirements.

In a similar fashion the trunks 1431 and 1432 outgoing from the line switches of the other two groups 1401 and 1402 are distributed among the district switches of the several selector groups.

The trunks outgoing from the different selector groups may lead through as many succeeding switches as are necessary. In the system illustrated, however, these trunks lead to group selector switches, which in turn, have access to connector switches for making connection with called subscribers' lines. The group selectors and connectors constitute terminal line groups of which there may be any suitable number as, for example, five. Two of these groups 1440 and 1441 are illustrated. The group 1440 comprises a plurality of group selectors 1442, 1444, etc., and a plurality of connector switches 1443 and 1445. The second group 1441 consists of group selectors 1446 and 1448 and connector switches 1447 and 1449. In like manner other terminal line groups are employed each comprising as many group selectors and connectors as are necessary.

Trunks 1423 which lead from the group 1407 of district switches are multiplied to appear in all district selectors of that group and lead to the group selectors of the several terminal line groups. While only a few trunks are illustrated, it is understood that these are symbolical of all groups and that each selector group is provided with at least one group of trunks leading to each of the terminal line groups and appearing in the group selector switches 1442, 1444, 1446, 1448, etc. Likewise, the trunks outgoing from the second and third selector groups 1408 and 1409 are multiplied before all the district switches of the respective groups and lead to the group selector switches of the several terminal line groups. Several group selectors in each terminal line group have access through interconnecting trunks to the different connector switches, which in turn, have access to the called lines.

In accordance with the division of the dis-

trict selectors into groups, so is the controlling equipment arranged on a similar plan. In Fig. 15 the elements 1500 to the left of the left hand vertical broken line represent controlling equipment which is individual to the first group 1407 of district switches. The elements 1501 represent the controlling equipment individual to the second group 1408 and the elements 1502 represent the controlling equipment individual to the third group 1409. The controlling equipment 1500 consists of a plurality of register senders 1503, 1504, 1505, 1506, a common district marker 1507 and a number of sender selector switches 1508 and 1509. The function of the sender selector switches 1508 and 1509 is to connect to an idle sender 1503, 1504, etc., any one of the trunks leading from the line switches to the switches of group 1407. As soon as the sender has received the record it becomes associated with the common district marker 1507, which in turn, becomes associated with the particular district selector of the group 1407 to which the extended calling line leads.

In a like manner the sender selectors of the second and third selector groups serve to connect trunks incoming to the district switches of these groups through to the register senders 1510, 1511, 1516 and 1517, which are in turn associative with the corresponding district markers 1513 and 1519. The district marker 1513 is associative with any one of the district switches of the group 1408, while the district marker 1519 is associative with any one of the district switches of the group 1409.

For controlling the terminal line group switches there are provided a number of line markers 1523, 1524, one for each of the terminal line groups. The marker 1523, for example, is individual to the group 1441 while the marker 1524 may be individual to the group 1440. The marker 1523 serves to control the group selector and connector switches and to this end it may be associated with any group selector and with any connector in the group it controls. The marker 1523 is associative with any one of the senders relating to any channel in the exchange. By this means any sender that has been taken for use may be connected to any line marker to control a group selector and connector switch in any terminal line group.

General description of system and apparatus.

The line switch 100, selector switches 300 and 400, connector switch 500 and the sender selector switch 600 employed in the system are of the coordinate type such as shown and described in British Patent No. 183,438, issued to Western Electric Company, Limited, accepted September 6, 1923, and in the

5 patent of S. B. Williams, No. 1,517,331, granted Dec. 2, 1924. Reference may be had to the latter patent for a more complete disclosure of features which are not specifically detailed in the following descriptions. The subscribers' lines enter the exchange and appear in the coordinate line switches 100 in vertical rows 110 and 111, each line having access to a group of horizontal links such as 10 107 and links 108 and 109. Line 101, for instance, has access to the group of links containing the links 106 and 107. Each of the 15 outgoing trunks 114 and 115 occupies a full vertical row of contacts 112, 113 and leads to the district switches.

20 Trunk 114, which is shown in full, appears in the district switch 300 in the vertical row of contacts 308. Another trunk 115 is shown occupying the vertical row of contacts 309. District selector switch 300 also has a plurality of groups of outgoing trunks appearing in rows 311, 312, 313, etc. Each 25 outgoing trunk is shown having an appearance before a single horizontal link such as the links 303, 304, 305, 306 and 307. These trunks are multiplied as explained to appear before corresponding horizontal links in all of the district switches of the same group. 30 Since the subscribers' lines as called lines are divided into a number of groups as called lines known as terminal line groups the trunks outgoing from the district switches are arranged as explained hereinbefore to have access to any of the terminal line groups of switching apparatus. The 35 group of trunks appearing in the upper section 302 of the vertical row 311 in switch 300 lead to the group selector switches of a particular terminal line group. One of these trunks 350 is shown leading to the group selector switch 400. The group of trunks occupying the lower section 301 of the same vertical row may lead to the group 40 selectors of the same or of a different terminal line group as desired. Other groups outgoing from the district switches are distributed to other terminal line groups. In addition to these groups of trunks, the district switches may have access to trunks extending in other directions.

45 The groups of trunks outgoing from the group selector 400 and from other group selectors in the same terminal group are distributed to a suitable number of connector switches. One of these connectors 500 is shown and a single trunk 422 is illustrated. The called subscribers' lines appear in the connector switches in groups. For 55 instance, the vertical rows 524 and 525, each represents a group of subscribers' lines. Each line is accessible over a group of horizontal links. The line 516 appears in the 60 group occupying the vertical row 525 and is accessible by a group of links, two of which

501 and 502 are shown. A second line 526 in the same group is accessible to another group of horizontal links 504, 505.

55 The district marker shown in Figs. 9 and 10 includes two sets of testing relays 1000 and 1003. The set 1000 serves to test the horizontal links of the section 302 in any district selector switch of this group and also to test the outgoing trunks which have access to these horizontal links. A connecting device 1002 which comprises a number of multi-contact relays 1015, 1016, etc. serves to connect the set of relays 1000 with the proper group of outgoing trunks, the multi-contact relays each being individual 60 to a different group. Likewise, the other set of the test relays 1003 serves with respect to the set of horizontal links 301 in all switches and the outgoing trunks to which these links have access. Also a connecting device 1004 consisting of multi-contact relays 1022, 1023, 1019, 1020, 1025 and 1026 serves to connect the marker testing relays with the individual switches of the group. Relays 1023, 1020 and 1026, for instance, are individual to the particular district switch 300 illustrated in the drawing.

65 The line marker shown in Figs. 11 and 12 includes a plurality of registers 1200, 1201 and 1202 which receive numerical records from the controlling sender. It also includes the multi-contact relay translating device 1204 which is operated according to the settings of the registers to select the magnets 514, 515 individual to the different vertical rows of contacts in the connector switches in which subscribers' lines terminate. Moreover, the line marker includes a multi-contact relay translating device 1203 which serves to associate the register 1201 with a connecting device 510 individual to the proper connector switch 500. The device 510, consisting of relays 511, 512, etc. serves to associate certain test relays with the horizontal links of the group having access to the called lines of the desired units designation. In Fig. 11 the set of testing relays of the marker are associative through the multi-contact relay connecting devices 401 and 402 with the groups of trunks outgoing 70 from the selector switch 400 and other switches and with the horizontal links of these group selectors.

75 *Detailed description of establishment of a connection.*

80 Consider that the subscriber of line 101 desires to hold conversation with the subscriber of line 516 appearing in the same central office. It may also be assumed that the directory number of the line 516 is 1 2 3 4. When the calling subscriber removes his receiver from the switchhook, a circuit is closed from battery through the winding of line relay 121, inner contact of cut-off 85

relay 120, conductor 104, through the substation loop, conductor 103, to ground through the outer contact of relay 120. Relay 121 operates and a circuit is closed from battery through the winding of relay 129, right back contact of relay 128, left contact of relay 121, conductor 156 to ground.

Relays 128, 129 and 130 enclosed within the broken rectangle pertain to the vertical group of lines in the row 110 of the switch 100. These relays are brought into action whenever one of the lines of the corresponding group initiates a call.

Relay 129 completes a circuit from battery through the winding of relay 131, inner front contact of relay 129 to the grounded conductor 156. Relay 129 also closes a circuit from battery through the left hand winding of relay 130, outer front contact of relay 129, left back contact of relay 135, outer right contact of relay 137, conductors 158 and 156 to ground. Relay 130 operates and closes a circuit for relay 128. Relay 128 locks through its left contact and the contacts of relays 131 and 132 to ground. Relay 130, in operating, completes a circuit from battery through its right hand winding and inner right contact, winding of relay 135, outer right contact of relay 137, conductor 158 to ground. Relay 135 operates and closes a circuit from battery through the winding of slow-to-release relay 136, inner right contact of relay 135, inner right back contact of relay 137, conductor 158 to ground. Relay 136 closes a substitute holding circuit for relays 130 and 135.

With relay 135 operated a circuit is closed from battery through the winding of the vertical operating magnet 116, outer right front contact of relay 130, left front contact of relay 135, contact of relay 136, conductor 158 to ground. The magnet 116 operates and prepares the contacts in the vertical row 110. Magnet 116 also closes a circuit from ground through its contact, conductor 159, inner contact of relay 134, outer left contact of relay 130, right contact of relay 121, left hand winding of the horizontal group relay 122 to battery. Relay 122 is a group relay individual to the group of horizontal links including the links 106 and 107. Similarly, relay 123 is a group relay individual to the other group of horizontal links illustrated.

Relay 122 operates and closes a circuit from battery through its right hand winding and right contact, right back contact of relay 123, winding of relay 134, conductor 159 to ground. Relay 134 operates in this circuit. Another circuit is closed from battery through the winding of the vertical operating magnet 118, brush 144 of allotter switch 143, contact of slow release relay 139, left contact of relay 137, outer right contact of relay 135, conductor 158 to ground. It is

assumed that the first one of the outgoing trunks 114 is idle and that the allotter switch 143 is standing in a position to allot this trunk as shown in the drawing. The allotter switch 143 has a position for each of the several trunks which lead out of the line switch 100 to the succeeding district selectors. Consequently, the vertical magnet 118 relative to the idle trunk 114 operates and prepares the contacts in the vertical row 112. Magnet 118, in operating, completes a circuit from battery through its winding and inner contact, conductor 160, winding of relay 137, outer right contact of relay 135, conductor 158, to ground. Relay 137, however, being shunted by the circuit above traced does not operate this time. Magnet 118, furthermore, closes a circuit from ground through its outer contact, conductor 151, winding of trunk relay 146 to battery. With relay 146 operated a circuit is completed from battery through the winding of relay 139, winding and contact of stepping magnet 138, brush 145, contact of relay 146 to ground over conductor 151. The magnet 138 operates, interrupts its own circuit and advances the brushes 144 and 145 to the next set of terminals. If the following trunk is idle then the allotter switch comes to rest, but if it is busy, the switch continues until an idle trunk is found. When the switch leaves the position shown it opens the shunt around relay 137 and this relay operates in series with magnet 118. Relay 137 opens the circuit of relay 136 which commences to deenergize. Relay 136 being slow, holds its armatures for an interval after the release of relay 137 which is sufficient for certain operations to take place.

During the interval mentioned a circuit is closed from ground over conductor 158, inner right front contact of relay 137, outer contact of relay 134, left back contact of relay 123, left front contact of relay 122, back contact of relay 127, assuming the first link 107 is idle, winding of magnet 125 to battery. Magnet 125 operates and effects a connection between the link 107 and the incoming line and also between the link and the outgoing trunk 114. Immediately that this connection is established, a circuit is closed from battery through the winding of magnet 125, winding of relay 127, contacts of the switch 100, over the sleeve conductor to ground at the outer contact of magnet 118. Relay 127 remains normal in this circuit to prevent a false operation of a succeeding magnet as 124. Another circuit is closed from battery through the winding of cut-off relay 120 over the sleeve conductor to ground at the contact of magnet 118. Relay 120 opens the circuit of relay 121, which in turn, opens the original energizing circuit of relay 129.

Should another line in the same vertical group attempt simultaneously to make a call while a subscriber in a succeeding vertical group is calling his attempt to make such a call will be unsuccessful. When the line relay 121 releases following the opening of its circuit by relay 120, it opens the holding circuit of relay 131, but since the second subscriber in the same group is calling relay 131 is held energized over a parallel circuit through the left contact of the line relay similar to relay 121. Relay 131 in remaining energized preserves the locking circuit of relay 128 which prevents the reenergization of relay 129. A second subscriber in the first group, or any group therefore, cannot succeed in making a call until all simultaneously waiting calls in subsequent groups have been handled. In this latter event a series circuit is closed for relay 132 through the back contacts of all relays similar to relay 129 and relay 132 operates to unlock relay 128.

At the instant relay 146 energizes the ground potential on conductor 151 is extended through the contact of this relay over conductor 150, through the back contact of relay 204, conductor 206, thence through the winding of relay 613. Relay 613 operates and locks through its winding and inner left contact, conductor 207, outer left back contact of relay 201 to ground. Relay 613 completes a circuit from ground through its outer right contact, conductor 209, winding of slow-to-release relay 204 to battery. Relay 204 operates and applies holding ground to the conductor 150, whereby magnet 125 and relays 127, 120 and 146 are held energized when magnet 118 becomes deenergized. Relay 613 operates similarly to the relay 120 of the line switch and brings the group relays 614, 615 and 616 and the control relays 619, 620, 621, 617, 622 and 623 into play to cause the extension of a connection through the sender selector switch 600 to the allotted idle register sender.

With relays 616 and 617 operated a circuit is closed from battery through the winding of vertical magnet 629, contacts of relays 616 and 617, outer right contact of relay 623 to ground. Magnet 629 operates and brings about the energization of relay 612, which in turn, locks in a circuit including the relay 621. Relay 617 also closes a circuit from battery through the winding of vertical magnet 631, brush 627 of allotter 626, contact of slow relay 625, left contact of relay 623, contact of relay 617 to ground. The magnet 631 operates and closes a locking circuit through its winding and contact and the winding of relay 623, the latter relay, however, remaining deenergized due to the shunt around its winding. Magnet 631 also closes a circuit from ground through its outer contact, conductor 638, through the brush 628, contact and winding of magnet 624, winding of relay 625 to battery. Magnet 624 steps the switch 626 forward to the set of terminals representing the next idle sender and in so doing removes the shunt from the winding of relay 623. Relay 623 opens the circuit of slow-to-release relay 622 which commences to deenergize. During the interval that relay 622 is deenergizing a circuit is closed from ground through the inner right front contact of relay 623, right contact of relay 621, left front contact of relay 612, front contact of relay 611, assuming the link 608 to be busy, back contact of relay 609, winding of the horizontal magnet 610 to battery. Magnet 610 operates the switch and connects the incoming trunk conductors through the link 607 to the group of conductors 632 leading to the selected idle sender.

Immediately that the connection is established a circuit is closed from battery through the winding of relay 201, conductor 210, contacts of switch 600, conductor 638 to ground at the contact of magnet 631. Relay 201 operates and opens the circuit of relay 613 which causes the deenergization of relays 612 and 619 provided no other sender is being sought through the same vertical group in the switch 600. Relay 201 also closes a holding circuit for the relay 204 which maintains a holding ground potential on the conductor 150. Furthermore, relay 201 connects the tip and ring conductors of the trunk through the sender selector switch to the impulse relay 700 of the sender. This results in the closure of a circuit from battery through the resistance 718, winding of relay 700, outer left contact of relay 703, conductor 640, through contacts of the switch 600, conductor 641, outer right contact of relay 201, conductor 149, thence through the line switch 100 and the subscriber's substation loop and returning over the other side of the line to conductor 148 to the inner right contact of relay 201, conductor 642, through the switch 600, conductor 643, inner left contact of relay 703, right hand winding of the balancing coil 701 to ground. Relay 700 operates and closes a circuit for slow-to-release relay 702. Relay 702 places ground on the holding conductor 720. This ground potential is transmitted by way of conductor 638 and results in a holding circuit for the magnet 610 and relays 609 and 201 in substitution of the circuit temporarily maintained by the vertical operating magnet 631.

Following the series of operations just related slow relays 136 and 622 become deenergized. Relay 136 opens the circuits of relays 130 and 135. Relay 130 opens the circuit of magnet 116 and relay 135 opens the holding circuit of magnet 118 and relay 137. Magnet 116 causes the release of relays

134 and 122. The release of relay 134 opens the shunt around the winding of relay 127 which operates in series with magnet 125. With the vertical magnets deenergized the 5 connection is now held through the line switch 100 due to the maintained energization of relay 125 which, as above mentioned, is held in a circuit closed to ground over the sleeve conductor 150. Relay 622, in releasing, similarly brings about a release of the corresponding elements in the sender selector switch 600 and the connection through this switch is now held by the magnet 610, the circuit of which is controlled by the slow 10 relay 702 in the sender. The apparatus is now in condition for receiving the first series of impulses. The calling subscriber, consequently, manipulates his impulse transmitter 163 to send a single impulse representing 15 the first digit of the wanted number.

At the time relay 702 operates it closes a circuit from battery through the winding of relay 706, left back contact of relay 704, left contact of relay 705, conductor 720, to 20 ground at the left contact of relay 702. Relay 702 also closes a circuit from battery through the resistance 739, left hand winding of relay 707 to ground at the right contact of relay 702. Relay 707, however, does 25 not operate since its winding is shunted by the following path: battery, through the resistance 739, contact of relay 700 to ground at the right contact of relay 702.

In response to the first interruption of the 30 line circuit by the calling subscriber, relay 700 releases and opens the shunt around the winding of relay 707 and this latter relay operates. Relay 707 closes a circuit from battery through the winding of relay 704, 35 outer left contact of relay 707 to the grounded conductor 720. Relay 704 operates and locks in a circuit through its left front contact, left contact of relay 705 to ground on conductor 720. Relay 704 opens 40 the original circuit of relay 703, but this latter relay remains energized in a circuit traceable through the outer right front contact of relay 707 to the grounded conductor 720. Relay 707 closes a circuit through the 45 left hand winding of relay 708 and relay 708 operates and closes a circuit from battery through its right hand winding and inner right contact to the grounded conductor 720.

50 Relay 708, in operating completes a circuit from battery through its left hand winding and left contact, conductor 724, outer right back contacts of counting relays 715, 714, 713 and 712 in series, winding of relay 712, outer left back contact of relay 713, conductors 725 and 726, outer right contact of relay 705, left front contact of relay 704, left contact of relay 705 to the grounded conductor 720. So long as relay 707 remains 55 operated relay 712 is shunted and does not

receive sufficient current in the circuit traced to energize. At the end of the impulse relay 700 operates and shunts relay 707 and this relay releases, opening the original circuit through the left hand winding of relay 708. Relay 712 now operates in series with the left hand winding of relay 708. Relay 712 locks in a circuit from battery over conductor 727, inner right contact and winding of relay 712, outer left back contact of relay 713 to ground over conductor 725.

It should be noted at this point that the armatures of the counting relay 712, which is also true of the remaining counting relays, are so arranged that the inner right contact 80 is closed slightly in advance of the opening of the outer right back contacts. By this arrangement the locking of the relay is certain to occur before the energizing circuit is opened.

Immediately that the relay 712 opens its back contact the circuit through the left hand winding of relay 708 is opened. It is to be noted that the left hand winding of relay 708, when energized in series with relay 712, is sufficient to overcome the differential effect of the right hand winding and maintain relay 708 actuated. However, since relay 712 is so adjusted that its right inner front contact closes before the right outer back contact is opened, a shunt effect is produced on the left hand winding of relay 708. This shunt circuit may be traced from battery, conductor 727, right inner armature and contact of relay 712, right outer 100 armature and back contacts of relays 712, 713, 714, and 715 in series, conductor 724 and thence through the left winding of relay 708 to battery. Since, however, there would be an appreciable interval between 105 the opening of the circuit through the left winding of relay 708 and the complete de-energization of said relay because of the self inductance of the left hand winding thereof, the effect of the right winding is to 110 produce an immediate de-energization and quick release of this relay when the flux produced by the right winding is differentiated by the declining flux of the left hand winding.

115 After the usual interval has elapsed following this impulse, slow-to-release relay 706 becomes deenergized and a circuit is completed from ground over conductor 720, contact of relay 706, right contact of relay 120 704, inner right contact of relay 705, conductor 722, right back contact of relay 808, winding of relay 807 to battery. Relay 807 operates and closes a circuit from battery through its winding and inner upper contact, thence over conductor 830, winding of relay 705, through contacts of relays 704 and 706 to ground. Relay 705, however, being shunted by the above circuit does not operate at this time. Relay 807 serves to con- 125 130

nect the counting relays to the register relays of the register 800. With relay 807 operated and relay 712 energized a circuit is closed from the grounded conductor 725, 5 outer left front contact of relay 712, conductor 728, outer right back contact of relay 717, conductor 729, conductor 831, contact of relay 807, thence in parallel one branch leading through the winding of relay 804 and 10 the winding of relay 832 to battery and the other branch leading through the winding of relay 823 to battery. Relay 804 operates and locks through its inner left front contact, conductor 825 to the grounded conductor 15 for 720. Relay 832 closes an obvious circuit for relay 808 which operates and locks to the grounded conductor 825. Relay 808 opens the shunt around the winding of relay 705, which energizes in series with relay 20 807. Relay 705 opens the circuit of relay 704, which in turn, opens the circuit of relays 705 and 807. Relay 807 disconnects the counting relay from the register 800. With relays 704 and 705 deenergized relay 25 706 again operates in the circuit above traced.

The subscriber operates his dial to transmit the second series consisting of two impulses and in the manner already fully explained relays 712 and 713 are operated. 30 Relay 713, in operating, opens the holding circuit of relay 712 which thereupon releases. After the proper interval has elapsed following the series, slow relay 706 releases and a circuit is closed from ground over conductor 722 as above traced, through the right front contact of relay 808, right back contact of relay 812, winding of relay 35 811 to battery. Relay 811 operates, connects the counting relays to the second register 801 and closes a locking circuit through its winding and inner upper contact, over conductor 830 as previously traced, through the winding of relay 705. Relay 705 being shunted does not operate at this time.

40 Since the counting relay 713 is operated a circuit is traceable from a grounded conductor 725, through the outer left front contact of relay 713, conductor 730, conductor 837, through contact of relay 812, winding of register relay 810 to battery. Relay 810 locks through its inner left contact to the grounded conductor 825. Relay 810 at its outer left contact closes a circuit for relay 812 which operates and locks to the conductor 825. Relay 812 opens the shunt around relay 705 which operates and 45 in the manner explained brings about the release of relay 704, relay 811 and also releases itself.

50 The subscriber next transmits the third series consisting of three impulses. In response to this series relays 712, 713 and 714 are operated and relays 712 and 713 successively release. After an interval relay 55 706 releases and closes a circuit as traced

over conductor 722, through the right front contacts of relays 808 and 812, right back contact of relay 816, winding of relay 815 to battery. Relay 815 operates, connects the counting relays to the register 802 and closes 70 a locking circuit for itself over conductor 830 through the winding of relay 705.

With relay 815 operated and the counting relay 714 energized, circuits are closed from ground over conductor 725, through the left 75 front contacts of relay 714, conductors 729 and 730, thence over conductors 831 and 837, through contacts of relay 815, windings of relays 813 and 814 to battery. Relays 813 and 814 lock through their inner left contacts to the grounded conductor 825. These relays also close a circuit for the relay 816 which operates and locks through its left contact to the conductor 825. Relay 816 opens the shunt around relay 705, which in 80 turn, operates in series with relay 815. In a similar manner to that already explained relay 705 brings about its own release and the release of relays 704 and 815.

The subscriber now transmits the final 90 series consisting of four impulses. In response to this series counting relays 712, 713, 714 and 715 are operated in succession and relays 712, 713 and 714 are released in succession. After an interval relay 706 releases and a circuit is closed by way of conductor 722, through the right front contacts of relays 808, 812 and 816, right contact of relay 820, winding of relay 819 to 95 battery. Relay 819 connects the counting 100 relays to the register 803 and closes a locking circuit for itself over conductor 830, through the winding of relay 705. With relay 819 operated and relay 715 operated a circuit may be traced from ground over conductor 725, outer left back contact of relay 712, inner left contact of relay 715, conductor 731, conductor 838, through contact of relay 819, relay 833 to battery. Relay 833 locks through its inner left contact to the 105 grounded conductor 825. Relay 823 closes a circuit for relay 820 which locks through its inner left contact to conductor 825. Relay 820 opens the shunt around relay 705 which brings about its own release and the 110 release of relays 704 and 819.

As soon as the thousands digit is recorded on the register 800, the sender is connected to the district marker in order that the record may be transferred thereto for determining the group selective operation of the district switch 300. When relay 808 operates a circuit is established from the grounded conductor 825, through the outer left contact of relay 808, conductor 839, winding 115 of relay 709 to battery. Relay 709 operates and locks through its outer contact to the grounded conductor 720. Relay 709 closes a circuit from the grounded conductor 720, through the outer left contact of relay 711, 120

65 125 130 135

inner contact of relay 709, conductor 732, winding of relay 904 to battery. Relay 904 is a start relay and serves to cause actuation of the sender connector 900 which is common to the group of senders including the sender shown in the drawing. It will be noted that when the line switch was operated to seize an outgoing trunk, should a trunk have been selected which leads to a district switch in a different group from that including switch 200, then a sender in a different group from the group including the sender shown, would have been selected. Consequently, the completion of the recording of the units digit in this latter sender would bring about the actuation of a start relay similar to relay 904 but associated with a connecting device similar to connector 900. In this case, the connecting device would be individual to the group of senders including the particular sender selected. When relay 904 operates, it closes a circuit from ground through its right contact, right contact of relay 907, winding of relay 908 to battery. Relay 908 operates and locks through its inner contact, middle back contact of relay 909, conductor 914, contact of slow relay 912 to ground. Relay 908 closes a circuit from battery through the right winding of relay 903, left contact of relay 904, left back contact of relay 906, outer contact of relay 908, middle back contact of relay 909, conductor 914 to ground. Relay 903 closes a circuit for relay 907. Relay 907, in turn, closes a circuit from battery through the left winding and contact of relay 903, left back contact of relay 905, left contact of relay 907, winding of relay 909 to ground over conductor 914. Relay 903 is locked and relay 909 operates in this circuit. Relay 908 now becomes released. Relay 909 causes a circuit to be closed for the multicontact relay 901, which is individual to the particular sender shown and serves to connect that sender with the district marker. Another multicontact relay 902 is individual to another sender and serves for a similar purpose. The circuit of relay 901 leads from battery through the winding thereof, inner right contact of relay 903, inner contact of relay 909 to the grounded conductor 914. Relay 901, in operating, closes a circuit from ground through its contact, outermost contact of relay 909, inner left back contact of relay 911, winding of relay 910 to battery. Relay 910 operates and closes a circuit from ground over conductor 914, through the middle front contact of relay 909, left contact of relay 910, conductor 915, outer left back contact of relay 1046, winding of slow-to-release relay 1048 to battery. Relay 1048 operates and closes a circuit for slow-to-release relay 1047.

65 Relay 910 also closes a circuit for the

vertical operating magnet 315 of the district switch 300 which controls the row of contacts in which appears the trunk 114. This circuit may be traced from ground over conductor 914, through the middle front contact of relay 909, left contact of relay 910, conductor 918, contact of relay 901, conductor 919, inner left contact of relay 711, conductor 734, contacts of switch 600, conductor 645, outer right contact of relay 205, conductor 212, winding of magnet 315 to battery. Magnet 315 prepares the contact in the row 308 and also closes a circuit through its right contact, conductor 327, winding of multicontact relays 1023, 1020 and 1026 in parallel to battery. These relays are individual to the district switch 300 and serve to connect the common marker thereto. Magnet 315 also completes a circuit from battery through the winding of relay 208, conductor 213, left front contact of magnet 315, conductor 215, through the inner left contact of relay 201 to the grounded conductor 150. Relay 208 operates and locks through its outer right contact to conductor 215.

Relay 910 also closes a circuit from the grounded conductor 914, through the right contact of relay 910, conductor 916, contacts of relay 901, conductor 917, outer right back contact of relay 822, right back contacts of relays 836, 835 and 805 in series, thence through the inner right back contact of relay 822, conductor 840, contact of relay 901, winding of relay 920 to battery. Relay 920 represents the thousands digit 1 in the marker and is operated due to the fact that this digit is registered on the register 800 of the sender. By inspection of the circuits it will be found that the other relays 921, 922, 923, etc. in the marker are operated when other thousands digits are recorded on the register 800 in the sender. With relay 920 energized a circuit is closed from the grounded conductor 916, through the contact of relay 920, conductor 925, winding of relay 1034, to battery. Relay 1034 is individual to the group of trunks which occupies the section 302 of the vertical row 311 outgoing from the district switch 300 leading to the terminal line switching group having access to called lines whose thousands digit is 1.

When relay 1034 operates it closes a circuit from ground through its lowermost contact, winding of relay 1046 to battery. Relay 1046 opens the circuit of relay 1048 which commences to release. During the release period of relay 1048, test relays 1000 are connected in the manner about to be described to the test conductors of the selected outgoing trunks to ascertain an idle trunk corresponding with an idle link. Relay 1046 closes a circuit from ground through its inner left contact, right front

- contact of relay 1047, upper front contact of relay 1034, conductor 1042, contact of relay 1026, conductor 1043, winding of the vertical operating magnet 318 to battery. Magnet 318 prepares the contacts in the row 311 and also closes a circuit from ground through its contact, conductor 334, contact of relay 1026, conductor 1044, winding of relay 1049 to battery.
- 6 The testing operation will now be described. To connect the test relays to the test conductors of the trunks the multi-contact relay 1015 individual to the group of trunks involved is operated over the following circuit: battery, through the winding of said relay, through the middle lower contact of relay 1034, conductor 1045, contact of relay 1026, conductor 1050, left contact of relay 1047, outer left front contact 15 of relay 1046, conductor 915 to ground. Relay 1015 connects the righthand windings of the double wound test relays of the group 1000 to the respective test conductors of the outgoing trunks. The left-hand windings 20 of these relays are connected through the contacts of relay 1023 to the test conductors of the corresponding horizontal link conductors. If, for example, the lowermost trunk in the section 302 of the vertical row 30 311 is busy, a circuit is closed from grounded sleeve conductor 335, through a contact of relay 1015, right contact of relay 1037, right-hand winding of test relay 1038 to battery. Relay 1038 operates and locks 36 through its right-hand winding, conductor 1051 to ground at the outer contact of relay 1046. If the corresponding horizontal link 40 306 is busy, a circuit is also closed from the sleeve conductor of the link by way of conductor 337, contact of relay 1023, outer left back contact of relay 1037, left winding of relay 1038 to battery. Either winding of any test relay is sufficient to operate the same. Provided the trunk 350 and its corresponding link 307 are both idle, the corresponding test relay 1041 remains de-energized.
- 45 After an interval the relay 1048 releases and a circuit is closed from ground over conductor 915, right contact of relay 1049, right contact of relay 1048, inner right contact of relay 1046, conductor 1052, thence through the contact of relay 1015, inner left front contact of relay 1036, inner left back contact 50 of relay 1039, winding of relay 1040 to battery. It will be noted that relay 1036 operates in a circuit closed through the left contact of relay 1038 to ground over conductor 1051. With relay 1040 operated a circuit 55 is closed from ground through the left contact of relay 1049, conductor 1053, through the contact of relay 1015, right front contact of relay 1036, right back contact of relay 1039, left front contacts of relay 1040, 60 contacts of relay 1023, thence over con- ductors 1054 and 1055, windings of horizontal magnet 326 to battery. The magnet 326 operates and effects a connection between the incoming trunk 114 and the idle outgoing trunk 350 by way of link 307. 70 Immediately that the connection is established the magnet 326 is locked in a circuit through its right-hand winding, contact of switch 300 to the grounded test conductor 150. After an interval following the release of relay 1048 relay 1047 becomes deenergized and in so doing opens the circuit of relay 1015 whereby the test relays are disconnected from the outgoing group of trunks. Relay 1047 also opens the circuit of the vertical 75 magnet 318. Magnet 318 causes the release of relay 1049. With relay 1047 deenergized a circuit is closed from ground through the inner left contact of relay 1046, right back contact of relay 1047, conductor 1057, winding of relay 911 to battery. Relay 911 causes the release of the district marker which is no longer required in connection with the present call.
- 80 Relay 911, in operating, closes a circuit for relay 912 but this relay being both slow to operate and slow to release, requires an interval of time before it retracts its armature. During this interval a circuit is closed from ground over conductor 914, through the outer left contact of relay 911, conductor 927, contacts of relay 901, conductor 928, winding of relay 711 to battery. Relay 711 operates and locks to the grounded conductor 720. Relay 911 also opens the circuit 95 of relay 910 which releases and opens conductors 915, 918 and 916. After a further interval relay 912 operates and removing ground from conductor 914 causes the release of the operated relays in Fig. 9, and the disconnection of the district marker from the sender by the release of multi-contact relay 901. The vertical magnets 315 and 318 having been deenergized, the connection through the district switch is held by the 100 maintained operation of the horizontal magnet 326.
- 100 When the magnet 315 releases a circuit is closed from battery through the winding of relay 205, inner right contact of relay 208, conductor 214, left back contact of magnet 315, conductor 215, through the contact of relay 201 to the grounded conductor 150. Relay 205 operates and locks through its inner right contact.
- 105 With relay 711 operated a circuit is closed from ground through the outer left contact of relay 820, conductor 841, outer right contact of relay 750, inner left contact of relay 710, inner right contact of relay 711, conductor 842, thence in parallel, through the winding of relays 843, 821 and 822 to battery. Since the thousands digit is 1, and since only the register relay 804 of the register 800 is operated, a circuit is now 110 115 120 125 130

completed through the front contact of one of the switching relays 821 and 822 for operating the relay 1112 to cause the connection of the register sender to the line marker which controls the final group switching equipment having access to the No. 1 thousand lines. This circuit leads from ground over conductor 842, as previously traced, through the outer right front contact of relay 822, right back contacts of relays 836, 835 and 805, inner right front contact of relay 822, conductor 930, winding of relay 1112 to battery. It will be obvious that should a different thousands digit have been dialed, for example, the digit 2, thousands register relay 805 alone will be operated, whereupon the grounded conductor 842 is extended by means of the right outer armature and front contact of relay 822, right armatures and back contacts of relays 836 and 835, right armature and front contact of relay 805, left armature and front contact of relay 822 to conductor 931. The grounding of conductor 931 serves to operate a start relay similar to relay 1112. In this case, the connecting device represented schematically by the rectangle 1170 is operated and associates the conductors coming from the sender with the line marker which is individual to the No. 2 thousand group of lines. Returning to the point where relay 1112 is operated as a result of the operation of register relay 804, an obvious circuit was completed for relay 1116. Relay 1116 locks through its right contact, outer right back contact of relay 1114, conductor 1140 to ground through the contact of slow relay 1117. Relay 1116 closes a circuit from battery through the right-hand winding of relay 1110, left contacts of relays 1112 and 1113, left contact of relay 1116, outer right back contact of relay 1114 to the grounded conductor 1140. Relay 1110 closes an obvious circuit for relay 1115. Relay 1115 closes a circuit from battery through the left-hand winding and contact of relay 1110, left back contact of relay 1111, left contact of relay 1115, winding of relay 1114 to grounded conductor 1140. Relay 1110 locks and relay 1114 operates in this circuit. A circuit is now established from battery through the multicontact relay 1108, outer right contact of relay 1110, inner left contact of relay 1114 to grounded conductor 1140. Relay 1108 operates and connects the sender to the line marker. Relay 1108 also closes a circuit through its contact, outer left contact of relay 1114, outer left back contact of relay 1119, winding of relay 1118 to battery.

One of the first things to take place upon the connection of the line marker to the sender is the closure of a circuit for the vertical operating magnet 406 of the group selector 400 in which terminates the selected

trunk 350 outgoing from the district switch 300. This circuit may be traced from the grounded conductor 1140, inner right contact of relay 1114, contact of relay 1118, conductor 1141, contact of relay 1108, conductor 1142, contact of relay 843, conductor 844, outer right contact of relay 710, conductor 740, contacts of switch 600, conductor 646, outer left contact of relay 205, outer left front contact of relay 208, over the tip 75 of the trunk 114, through the switch 300, over the tip of trunk 350, contact of relay 418, winding of magnet 406 to battery. Magnet 406 prepares the contacts in the vertical row of the switch 400 and closes a circuit for multicontact relay 412. Relay 412 connects the test relays of the line marker with the horizontal links of the switch 400 for testing purposes.

The record of the thousands, hundreds, tens and units digits is now transferred from the registers of the sender to the line marker. The relays 1218 and 1219 serve to determine whether the thousands digit is even or odd according to the combination in which they are operated. In the present case the digit being 1 and odd, the relay 823 alone in the sender is operated. Relay 823 closes a circuit from ground over conductor 1142 as above traced, contact of relay 823, conductor 845, contacts of relay 1108, conductor 1143, winding of relay 1218 to battery. A circuit is now closed from battery through the winding of multicontact relay 1228, left front contact of relay 1218, right back contact of relay 1218 to the grounded conductor 1141.

Another circuit may be traced from ground over conductor 1142, through the right contact of relay 810, conductor 846, contacts of relay 1108, conductor 1144, winding of relay 1215 to battery. Other circuits are traceable over conductor 1142, through the right contacts of relays 813 and 814, conductors 847 and 848, contacts of relay 1108, conductors 1145 and 1146, windings of relays 1206 and 1207 to battery. Still another circuit leads from ground over conductor 1142, through the right contact of relay 833, conductor 849, contacts of relay 1108, conductor 1147, winding of relay 1212 to battery. With relay 1215 operated a circuit is traceable from ground over conductor 1141, inner right back contacts of relays 1217 and 1216, inner right front contact of relay 1215, inner left back contact of relay 1214, winding of multi-contact relay 1226 to battery. A circuit is now closed from battery through the winding of relay 1230, contact of relay 1228, contact of relay 1226, conductor 1232 to the grounded conductor 1141. Relay 1230 operates and a circuit is established from ground over conductor 1232, contact of relay 1230, inner right back contacts of relays 1209 and 1208, inner right 125

130

front contact of relay 1207, inner left front contact of relay 1206, conductor 1233, contacts of relay 1228 and 1226, conductor 1234, winding of vertical magnet 515 to battery.

5 Magnet 515 operates and prepares the contacts in the vertical row 525.

Magnet 515 also closes parallel circuits for the multicontact relays 416 and 1220. Relay 416 connects the common test relays 10 with a group of trunks leading from the switch 400 to the connector switch 500 and also closes a circuit for the vertical operating magnet 408. Magnet 408 prepares the contacts in the associated row and closes a 15 circuit from ground through its contact, contacts of relay 412, conductor 403, winding of slow-to-release relay 1121 to battery. Relay 1121 closes a circuit from battery through the winding of relay 1138, back 20 contact of relay 1137, outer contact of relay 1121 to the grounded conductor 1141. Relay 1138 closes a circuit from ground over conductor 1141, through the front contact of said relay, winding of slow-to-release relay 25 1123 to battery. Relay 1123 closes a circuit for slow-to-release relay 1124, which in turn, completes a circuit from battery through the winding of relay 1125, front contact of relay 1124, conductor 1148, outer right front 30 contact of relay 1114 to the grounded conductor 1140. Relay 1125 locks to ground on conductor 1140.

The multicontact relay 1220 operates and connects the register 1201 to the connecting 35 device 510. Relay 1220 also closes a circuit from battery through the winding of relay 1235, contact of relay 1220 to the grounded conductor 1141. Relay 1235 completes a circuit from the grounded conductor 1141, 40 through its contact, thence through the inner right contact of relay 1213, inner right front contact of relay 1212, conductor 1236, contacts of relay 1220, winding of relay 511 to battery. Relay 511 associates the test relays 45 1222, 1224, etc. with the horizontal links of the group having access to the called subscriber's line 516.

The testing operation will now be explained. If the first trunk 420 in the selected group is busy, a circuit is closed from battery, through the right-hand winding of test relay 1134, inner right contact of relay 1136, contacts of relay 416 to the grounded 50 sleeve conductor of trunk 420. If the link 55 403 associated with trunk 420 is busy a circuit is closed from battery through the left winding of relay 1134, outer left back contact of relay 1136, contacts of relay 412, test conductor of the link 403, to ground.

60 It will be noted that the relay 412 which is individual to the switch 400 is operated at this time in a circuit closed by the vertical magnet 406.

65 The energization of either winding of the relay 1134 is sufficient to operate the same.

If the next trunk 421 or its associated link is busy or both are busy, the corresponding test relay 1131 is operated. Assuming, however, that the next trunk 422 and the link 405 are idle the relay 1128 remains deenergized. Relays 1134 and 1131, in operating, 70 lock through their right windings and contacts, conductor 1149, contact of relay 1121 to the grounded conductor 1141. Relays 1134 and 1131 also close respective circuits 75 for the relays 1135 and 1132 which extend to the grounded conductor 1149.

Another circuit may be traced from ground over conductor 1141, through the contact of relay 1121, inner left front contacts of relays 1135 and 1132, inner left back contact of relay 1129, winding of relay 1130 to battery. A circuit is now closed for the vertical operating magnet 513 of the connector switch. This circuit leads from 80 ground over conductor 1141, through the outer contact of relay 1121, outer right contact of relay 1130, middle right contact of relay 1129, contact of relay 416, conductor 424, winding of magnet 513 to battery. 85 Magnet 513 prepares the associated contacts and also closes a circuit from ground through its contact, conductor 518, contact of relay 416, winding of relay 1137 to battery. Relay 1137 operates and opens the 90 circuit of relay 1138. This latter relay, however, is slow to release and requires an interval before it retracts its armatures. Relay 1137 also closes a circuit from battery through the winding of the horizontal test magnet 509, contacts of relay 510, front contact of relay 1137, contact of relay 1121 to the grounded conductor 1141. Magnet 95 509 operates the test link 503 connecting the sleeve conductor of the incoming trunk with the sleeve conductor of line 516.

While the foregoing operations are taking place a test is made of the links 501 and 502 to determine an idle one. Assuming the link 501 is busy a circuit is completed from battery through the right-hand winding of relay 1222, left contact of relay 1221, contact of relay 511 to the grounded test conductor of link 501. Relay 1222 100 operates and locks through its left winding to the grounded conductor 1141. If the next link is idle the corresponding relay 1224 remains deenergized.

After the necessary interval relay 1138 105 becomes deenergized and opens the holding circuit of relay 1123. While relay 1123 is holding its armatures attracted, a test circuit is closed from battery through the winding of test relay 1122, left contact of relay 1123, outer contact of relay 1138, middle right contact of relay 1130, outer right contact of relay 1129, contact of relay 416, test conductor 425 of trunk 422, through 110 the test link 503 to the test conductor 521 of the called line. Assuming the line 516 115 120 125 130 135

- to be idle, no potential is found on the test conductor 521 and, consequently, relay 1122 fails to operate. After an interval relay 1123 releases and opens the circuit of relay 5 1124. While relay 1124, which is slow to release, is deenergizing a circuit is closed from ground over conductor 1141, right back contact of relay 1123, right contact of relay 1122, outer contact of relay 1125, conductor 1150, innermost right front contacts of relays 1135 and 1132, innermost right back contact of relay 1129, left front contacts of relay 1130, thence through contacts of relay 412, through the windings of magnet 411 to battery. Magnet 411 operates the selector switch 400 and immediately that the connection is effected, a circuit is closed from battery through the winding of relay 417, through contacts of the switch 400, thence to the grounded conductor 1141 as traced. Relay 417 operates and locks to the grounded sleeve conductor of the incoming trunk 350. Relay 417 closes a circuit for relay 418 which opens the circuit of magnet 406, which in turn, opens the circuit of relay 412. The connection through the switch 400 is now held by the horizontal magnet 411 which is locked in a circuit through its right winding, contacts of the switch 400, contact of relay 417 to the grounded sleeve conductor of the trunk.
- Another branch of the above mentioned circuit leads through the inner left contact of relay 1125, conductor 1151, right front contact of relay 1222, right back contact of relay 1224, winding of relay 1223 to battery. Relay 1223 operates and extends the grounded conductor 1151 through its right contact, conductor 1237, contact of relay 511, left winding of magnet 508 to battery. Magnet 508 operates the connector switch 500 and locks through its right winding and contacts of the switch to the grounded sleeve conductor 425.
- After an interval has elapsed relay 1124 releases. Relay 1125 remains energized and a circuit is established from the grounded conductor 1148, back contact of relay 1124, outer right contact of relay 1125, winding of release relay 1119 to battery. Relay 1119 closes a circuit for relay 1117 which, being slow to operate, requires an interval to retract its armature. Relay 1119 opens the circuit of relay 1118 which removes ground from the conductor 1141 bringing about the release of the several relays which have been held in circuits depending upon this grounded conductor. While relay 1117 is operating a circuit is closed from ground through its contact, right contact of relay 1119, conductor 1153, contacts of relay 1108, conductor 1154, winding of relay 710 to battery. Relay 710 operates and locks to the grounded conductor 720.
- After an interval relay 1117 operates and

removes ground from conductor 1140 causing the release of the remaining operated relays and magnets. Relay 1108 is also released to disconnect the register sender from the line marker. The horizontal test 70 magnet 509 releases and disconnects the test link 503 from the subscriber's line and from the trunk 422. With the vertical magnets 406, 408, 513 and 515 deenergized, the connection is held through the switches 400 75 and 500 by the maintained operation of magnets 411 and 508.

Relay 710, in operating, brings about the operation of relay 703 which causes the release of the sender. The circuit for relay 80 703 extends from battery through the winding thereof, outer left contact of relay 710, outer right contact of relay 750, conductor 841, to ground at the outer left contact of relay 820. Relay 703 opens the holding 85 circuit of relay 700 which releases and opens the circuit of relay 702. After an interval relay 702 releases and removes ground from the holding conductor 720, whereby all energized relays of the registers and all other 90 relays lock to the conductor 720 are released. lock to the conductor 720 are released. With the removal of ground from conductors 720 and 638 the horizontal magnet 610 of the sender selector is deenergized thereby 95 disconnecting the sender from the trunk.

The removal of ground from conductor 638 and the release of switch 600 also opens the holding circuit of relay 201. Relay 201 100 extends the tip and ring conductor of the trunk 114 through to the repeating coil 227. The extension of the calling line to the repeating coil closes a circuit for relay 203 which operates and provides a substitute circuit of relay 204 since the circuit 105 which previously held relay 204 is now open at the outer left contact of relay 201. Relay 201 at its inner left contact also opens the holding circuits of relays 208 and 205. Relay 208 completes the tip and ring conductors of the trunk 114 through to the right-hand windings of repeating coil 227. For a detailed description of the manner in which 110 ringing current is applied to the called line, reference may be had to the patent to S. 115 B. Williams, No. 1,517,331, granted December 2, 1924.

Release of the established connection.

After the conversation is finished and the calling subscriber replaces his receiver on the switchhook, relay 203 becomes deenergized. After an interval the slow relay 204 releases and removes ground from the sleeve conductor 150. This causes the deenergization of the operating magnet 125 of the line switch 100, relay 120, relay 146, the operating magnet 326 of the district switch 300, relay 417, the operating magnet 411 of switch 400 and the operating magnet 130

508 of the connector switch 500. The entire connection through the switches is thereby released and the apparatus is thereby restored to its normal condition.

5 *Called subscriber's line tests busy.*

In case the called line 516 is busy at the time a test thereof is made the test relay 1122 operates in the circuit previously traced and locks through its inner left contact to the grounded conductor 1141. Relay 1122 closes a circuit from the grounded conductor 1141, through its outer left contact, conductor 1155, contact of relay 1108, conductor 1156, winding of relay 750 to battery. Relay 750 locks through its left contact to the grounded conductor 720. Relay 750 closes a circuit from ground through the secondary winding of the busy tone coil 751, inner right contact of relay 750, left-hand winding of the balancing coil 701, condenser 741 to ground. Current flowing in this circuit induces a current in the right-hand winding of the coil 701 which is transmitted to the calling substation producing a busy tone in the subscriber's receiver.

After an interval relay 1123 releases but since relay 1122 is now operated the above traced circuits for operating the selector switch 400 and the connector switch 500 are not completed. In the manner described relay 1124 releases and operates the release relay 1119 which brings about a disconnection of the sender from the line marker. In this case, however, relay 703 remains de-energized since the operating circuit therefor is open at the outer back contact of relay 750. Consequently, the sender remains connected to the calling subscriber's line until he recognizes the significance of the busy tone and hangs up his receiver.

On replacing his receiver it opens the circuit of relay 700 which, as above described, brings about the release of the sender and the sender connector switch 600. Following this the line switch and the district selector switch 300 are released in the manner explained.

The particular call described in detail involves the extension of the connection from a calling subscriber's line through a line switch to a given district selector in a certain channel, thence into a particular terminal line group where it is further extended through a group selector and connector switch to the wanted line. It will be understood in comparing the detailed circuits with the schematic diagram of Figs. 14 and 15 that such a connection is typical of the exchange and may involve calling lines of any class, any of the several channels of district switches and any of the terminal line groups of switching equipment.

In the foregoing description, it has been assumed that the subscriber's line 101 be-

longs to the flat rate class, consequently, the line switch 100 and district switch 300 are of the corresponding class; i. e., whenever a subscriber's line is arranged for service on a flat rate basis, a particular type of line switch and district switch will operate. Similarly, should a subscriber's line be limited to coin box service, a line switch and district switch adapted for the extension of such lines would be instrumental in effecting the connection. From this it will be seen that the particular district switch selected for use will depend not only upon the particular district trunk selected outgoing from a line switch, but also upon the class of service for which a calling line is adapted. A reference to Figs. 14 and 15 will render obvious this arrangement. For example, subscribers' lines terminating in switches of group 1402 as hereinbefore mentioned are arranged for coin box service. Should a subscriber on any of these lines initiate a call then a coin district switch as 1414 in any of the groups 1407, 1408, etc. would be effective in completing the connection. Thus, the selection of a particular district switch is dependent not only upon the trunking between the line and district switches but also upon the class of service to which a calling line is adapted.

What is claimed is:

1. In a telephone system, selective switches arranged in groups, means for extending incoming calls to the switches of each group, controlling mechanisms, one for each group of switches comprising a number of register senders and a marker associative with any of said senders, and means controlled by said marker for operating any selective switch of the corresponding group.

2. In a telephone system, selective switches arranged in groups, means for extending incoming calls to the switches of each group, controlling mechanisms one for each group of switches comprising a number of register senders and a common marker, means for connecting any sender to the said marker, and means controlled by said marker for operating any selective switch in the corresponding group.

3. In a telephone system, selective switches arranged in groups, means for extending calls to the switches of each group, controlling mechanisms one for each group of switches comprising a number of register senders and a common marker, means for connecting any sender to the said marker, means for connecting said marker to any switch of the corresponding group, and means controlled by said marker for operating the selective switch to which it is connected.

4. In a telephone system, selective switches arranged in groups, means for extending incoming calls to the switches of each group,

- controlling mechanisms one for each group of switches comprising a number of register senders and a marker associative with any of said senders, means for setting up records
- 6 on said senders, means for transferring the record from any sender to the associated marker, and means controlled by such marker for operating any selective switch of the corresponding group.
- 10 5. In a telephone system, telephone lines, equivalent selective switches arranged in groups, means for extending said lines to the switches of any of said groups, controlling mechanisms one for each group of
- 15 switches comprising a number of register senders and a marker associative with any of said senders, and means for operating any switch in a given group under the control of the corresponding marker.
- 20 6. In a telephone system, a telephone line, a number of groups of selective switches, means for extending said line to the switches of any group, controlling devices one for each group of switches comprising register
- 25 senders and a marker associative with any of said senders, means for connecting said line to the controlling device associated with the particular group of switches to which such line is extended, and means controlled
- 30 by the marker for operating a switch in the corresponding group to further extend said line.
7. In a telephone system, a telephone line, a number of groups of selective switches,
- 35 means for extending said line to any switch of any group, controlling mechanisms, one for each group of switches including a number of register senders and a marker associative with any of said senders, means for
- 40 connecting said line to a sender associated with the particular group of switches to which such line is extended, means for connecting the corresponding marker to the particular switch to which said line is extended, and means controlled by such marker for operating the selective switch to further extend the line.
8. In a telephone system, telephone lines, groups of equivalent selective switches, preliminary switches for extending one of said lines to the switches of any of said groups, controlling devices, one for each group of switches consisting of a number of register
- senders and a marker mechanism associative with any of said senders, and means controlled by said marker for operating any selective switch of the corresponding group. 55
9. In a telephone system, telephone lines of different classes, a number of groups of selective switches, means for extending said lines to the switches of any of said groups, controlling mechanisms, one for each group of switches including a number of register senders and a marker associative with any of said senders, and means controlled by a 60 marker for operating any selective switch of the corresponding group. 65
10. In a telephone system, telephone lines of different classes, equivalent selector switches arranged in groups, preliminary 70 switches for extending the lines of any class to the selective switches of any of said groups, controlling mechanisms one for each group of switches comprising register senders and a marker associative with any of 75 said senders, and means controlled by said marker for operating any one of the selector switches of the corresponding group to further extend said lines.
11. In a telephone system, coordinate selector switches arranged in groups, means for extending incoming calls to the switches of each group, controlling mechanisms, one for each group of switches comprising a 80 number of register senders and a marker associative with any of said senders, and means controlled by said marker for operating any selector switch in the corresponding group. 85
12. In a telephone system subscribers' 90 lines of different classes, groups of selector switches, said groups comprising classes of switches corresponding to said classes of lines, means for extending a line of any class to a switch of the corresponding class 95 in any of said groups, controlling mechanisms, one for each group of switches comprising a number of register senders and a marker associative with any of said senders, and means for operating any switch in any 100 group under control of the corresponding marker.

In witness whereof, I hereunto subscribe my name this 29th day of March A. D., 1923.

SAMUEL B. WILLIAMS.
